UNITED STATES PATENT OFFICE.

JAMES B. LADD, OF ARDMORE, PENNSYLVANIA, ASSIGNOR TO UNITED STATES CAST IRON PIPE AND FOUNDRY COMPANY, OF BURLINGTON, NEW JERSEY, A CORPORATION OF NEW JERSEY.

AUTOMATIC SKID.

Application filed July 14, 1926. Serial No. 122,490.

My invention relates to centrifugal pipe casting machines of the type in which the mold is a permanent part of the machine and the cast pipe is withdrawn therefrom. In 5 such machines inclined skids are convenient means for receiving the pipes but are, unless retracted, in the way of moving parts of the casting machine during its normal operation. Such skids when in operative position or 10 when being brought to operative position are liable to contact with enlarged portions of the pipe with consequent danger of breakage.

The object of my invention is in the first place to provide retractable skids with elastically supported terminal ends which can rock out of the way if they contact with enlarged portions of the pipe and in the second place to provide the retractable skids with operating mechanism working in synchronism with 20 the operations of the casting machine whereby the skids are moved to operative position at the time when the cast pipe is being withdrawn from the mold and withdrawn after the delivery of the pipe.

25 Detailed features of my invention will be best understood as described in connection with the drawings, which show it in what I believe to be its best embodiment and in which

Figure 1 is a plan view of my improved 30 apparatus shown in an intermediate position during the movement of the carriage, in which the pipe is partially withdrawn from the mold.

Figure 2 is an elevation of the apparatus 35 shown in Fig. 1, with the parts in the same relative positions.

Figure 3 is a similar elevation with the carriage and mold shown as in the position in which the pipe is entirely withdrawn from 40 the mold and rests upon the skids.

Figure 4 is a cross sectional elevation on the line 4—4 of Fig. 1.

Figure 5 is a cross sectional elevation on the line 5—5 of Fig. 1.

45 Figure 6 is an elevation on an enlarged scale of the end of one of the skids with the pipe shown resting upon it.

Figure 7 is a cross section on the line 7—7 of Fig. 6.

50 Figure 8 is a cross section on the line 8—8 of Fig. 4.

Figure 9 is a sectional view taken on the

same plane as Fig. 7, showing the operation of the hinged skid ends in connection with the bell of the pipe.

55 Figure 10 is an end elevation, and

Figure 11 is a plan view showing the operation of the hinged elastically supported skid end in connection with the bell end of the pipe. Figures 12 and 13 show the same parts 60 with the hinged end of the skid shifted to avoid breakage by reason of its contact with the bell end of the pipe.

A, A indicate tracks for the mold supporting carriage, supported on a frame, indicated 65 at A¹, A² indicating an extension of the frame which supports the pipe gripping mechanism indicated at E. B is the mold carriage supported on the track through the flanged wheels indicated at B¹, B², etc. C indicates 70 the mold rotatably supported in the carriage B. D indicates the centrifugal cast pipe. E as before mentioned is the pipe gripping mechanism. f, f, are pipe receiving skids located at one side of the machine and on which 75 the pipes are delivered by the skids indicated at G, G. F, F, indicate brackets secured to the casing A¹ and supporting rollers F¹, F². The skids G rest upon the rollers F¹ and are also indicated by flanges F³ extending laterally 80 from a tongue F² of the bracket F as is best shown in Fig. 8. Near the end of the skids G a hinge pin G³ is supported in lugs G² forming a hinged support for the skid ends supporting piece indicated at H, which is formed 85 with slots as indicated at H¹ and to which the end pieces of the skids are secured by bolts H³ and adjusting screws indicated at H⁴. The supporting piece H and skid end H² are normally supported in the position shown in 90 Figs. 6 and 7 by the springs G⁴, which springs, however, permit them to move out of position as shown for instance in Fig. 9. The extreme end of the piece H² is bent at an angle as indicated at h².

95 I is a bracket extending out from the carriage B² and supporting a cam I¹, best shown in Figs. 1 and 4. In this cam is indicated a cam roller J¹ secured on the end of a lever J, J², pivoted at I³ on a pivot supported by a bracket I² and having its end J² connected by a link J³ with a pivot pin J⁷ on arm J⁶, which in turn is pivotally supported at J⁸ on the stirrup J⁹ and pivotally connected at 100

J^{10} with the link J^{11} pivoted to the end of the skid G at J^{12} . The link J^3 is formed with detent notches as indicated at J^4 and J^5 .

K is a cam best shown in Figs. 2 and 3, this cam being secured to the bottom of the reciprocating mold carriage and operating upon the end of a rod K^1 , the upper end of which is guided by a strip K^2 while the lower end is pivotally connected at K^3 with a lever arm K^4 pivoted at K^5 and carrying a detent finger K^6 at its free end, which when in its lowermost position engages in one of the detents J^4 or J^5 .

In operation the mold carriage B is given a reciprocating movement during the pouring of the metal and again during the operation of withdrawing the cast pipe from the mold, this apparatus being of the familiar De Lavaud type. The withdrawal of the pipe being effected as indicated by a gripping device E entering the bell end of the pipe and holding the pipe in fixed position while the carriage and mold move away from it, as indicated in Fig. 1. When the carriage is in its extreme right hand position both of the skids G are necessarily retracted and held locked in retracted position by the engagement of the detent finger K^6 with the detent notch J^4 as indicated in Fig. 5. As the carriage moves toward the left the cam K pressing against the upper end of the rod K^1 pushes it down and through the connections described, lifts the locking finger K^6 out of the detent notch and following this release of the link J^3 , the cam I^1 is so formed as to act upon the roller J^1 and shift the lever from the position shown in Fig. 5 to that shown in Fig. 4, as a result of which the skid G is thrust forward to the position shown in Fig. 4 and at the right hand of Fig. 1, so as to extend beneath the pipe as the right hand end of the pipe is freed from the mold. The skid is locked in this position by the detent K^6 being permitted by the cam K to enter the detent notch J^5 as shown in Fig. 4. As the carriage B moves further to the left the cams K and I^1 engage the mechanism of the second skid, releasing it from retracted and locked position, forcing it inward to a position beneath the pipe and locking it in this position, the mechanism being in all respects that described in connection with the right hand of the two retractable skids.

It will be obvious, of course, that as the mold carriage after delivery of the pipe moves toward the right, the action of the molds will be exactly the reverse of that above described, each skid being successively unlocked, retracted and again locked in retracted position.

It will also be understood that when the pipe is freed from the mold it will roll down on the inclined skids G on to the fixed receiving skids marked f , as best indicated in Fig. 4.

65 The elastically supported end piece for the retractable skids shown in detail in Figs. 6 to 13, are hinged and shaped as shown, so that in case they come in contact with the bell ends of the pipe, breakage will be avoided by the yielding of the skid ends.

Having now described my invention, what I claim as new and desire to secure by Letters Patent is:

1. In combination with a centrifugal pipe casting machine having a longitudinally reciprocating mold carrying carriage, approximately horizontal pipe receiving skids longitudinally movable in a direction transverse to the line of movement of the carriage to and from a pipe receiving position and a retracted position in which they will be outside of the path of the carriage and means actuated by the carriage for shifting the skids to pipe receiving position as the carriage moves away from their path of movement and retracting them as the carriage moves in a reverse direction.

75 2. In combination with a centrifugal pipe casting machine having a longitudinally reciprocating mold carrying carriage, approximately horizontal pipe skids inclined to a horizontal plane and longitudinally movable in a direction transverse to the line of movement of the carriage to and from a pipe receiving position and a retracted position in which they will lie outside of the path of the carriage and means actuated by the carriage for shifting the skids to pipe receiving position as the carriage moves away from their path of movement and retracting them as the carriage moves in a reverse direction.

90 3. In an apparatus having the features of claim 1 the construction of the skids with terminal sections hinged to the outer ends 95 of the skids and normally held in operative position by springs.

95 4. In an apparatus having the features of claim 1 the combination therewith of automatically acting locking means securing the skids in pipe receiving position and means operated by the movements of the carriage for releasing the locking means prior to the withdrawal of the skids.

100 5. In an apparatus having the features of claim 1 the constructive features by which the individual skids are independently movable and are actuated successively by the means actuated by the carriage.

JAMES B. LADD.
